UNITED STATES PATENT OFFICE.

ANTHONY J. HEROLD, OF OMAHA, NEBRASKA.

CLAMP.

1,272,259.

Specification of Letters Patent.

Patented July 9, 1918.

Application filed February 9, 1918. Serial No. 216,263.

To all whom it may concern:

Be it known that I, ANTHONY J. HEROLD, citizen of the United States, residing at Omaha, in the county of Douglas and State 5 of Nebraska, have invented certain useful Improvements in Clamps, of which the following is a specification, reference being had therein to the accompanying drawing.

This invention has reference generally to 10 improvements in that class of inventions known as wood working, and more particularly relates to a clamp.

As the primary aim and object, the present invention contemplates the provision of 15 a clamp, the sections of which are adapted to be adjustable with respect to each other, manually adjustable means being provided for holding the sections of the clamp in various positions of adjustment.

20 It is an equally important object of this invention to provide an improved movable jaw on one of the sections with which cooperates the novel manually operable adjusting means for moving the jaw into engagement with a piece of work subsequent to adjustment with the sections of the clamp.

25 More particularly, the present invention embraces the provision of resiliently actuated pawls in the handle forming a part of the adjusting means for coöperation with the teeth on the sleeve adjusting nut.

30 As a further improvement, the invention embraces the provision of improved means for governing the action of the pawls to consequently permit of the jaw being adjusted toward a piece of work or away from a piece of work.

More specific objects of this invention 35 consists of the provision of improved retaining means for preventing accidental disengagement of the sections; improved means for preventing accidental disengagement of the keeper forming a part of the means for holding the sections in a relatively adjustable position; to provide means for readily connecting the block which adjustably supports the movable jaw to one of the bracket arms on one of the sections of the clamp.

45 Among the other aims and objects of this invention may be recited the provision of a device of this character with a view to compactness, in which the number of parts are few, the construction simple, the cost of production low and the efficiency high.

50 Other objects as well as the natural characteristic features and scope of this inven-

tion will be more readily apparent from the following description taken in connection with the accompanying drawings and pointed out in the claims forming a part of this 60 specification.

The invention is clearly illustrated in the accompanying drawings, in which Figure 1 is a side elevation thereof;

Fig. 2 is a front elevation of the invention; 65

Fig. 3 is an enlarged vertical section taken through the adjustable jaw;

Fig. 4 is a horizontal section taken on line 4—4 of Fig. 3;

Fig. 5 is an enlarged transverse section 70 taken through the means for holding the sections in a relatively adjustable position;

Fig. 6 is a perspective of one of the sections of the clamp;

Fig. 7 is a perspective detail of the means 75 for holding the sections in adjusted position.

Fig. 8 is a section taken on line 8—8 of Fig. 3 in a direction in which the arrows point. 80

Fig. 9 is a fragmentary rear elevational detail of one of the sections.

Similar characters of reference are employed in all of the above described views, 85 to indicate corresponding parts.

Referring now, more particularly, to the accompanying drawings, there is provided a clamp, consisting of a channel-shaped section 1 and a relatively flat section 2, preferably rectangular in cross section, the latter 90 being slidably received in the channel-shaped section 1. A bracket arm 3 is formed on the outer end of the channel-shaped section while a rigid jaw 4 is rigidly connected to the outer end of the bracket arm. Another 95 bracket arm 5 is formed on the outer end of the section 2 and is longer than the arm 3 while adjustably mounted on this arm for coöperation with the jaw 4 is a movable jaw 6 swiveled to a threaded shank 7. 100

With a view toward providing improved means for adjustably connecting the movable jaw to the bracket arm 5 a block 8 is carried by the outer face of the arm and is provided with a longitudinally extending threaded bore 9 for adjustably accommodating the threaded shank 7. The body is also provided with a transverse recess 10 which intersects the bore and adjustably mounted on the shank and positioned within the recess is a sleeve nut 11 provided on its outer periphery with a plurality of uniformly 110

spaced teeth 12. A handle is now employed and consists of complementary sections 13, the outer ends of which are semi-circular in cross section while the inner ends are reduced and terminate in disks 14 which are arranged about the outer periphery of the adjacent sleeve nut 11 spaced from each other by the teeth 12. Double acting pawls 15 are pivotally mounted at points substantially intermediate their ends by means of fastening devices 16 which extend through the plates, the pawls being arranged upon opposite sides of the sleeve nut 11 and being engageable with the teeth 12. Suitable resilient means such as a coiled expansion spring 17 has its respective ends secured to the inner ends of the pawls for consequently normally holding the engaging ends thereof in engagement with the teeth. In order to hold either one of the pawls out of engagement with the teeth, a governor band 18 is partially rotatably mounted on the outer ends of the sections and has the inner edge thereof provided with a recess 19, the ends of which constitute shoulders 20 while the inner periphery of the band is preferably beveled toward the respective ends of the shoulders 20 so that the wide portion may ride freely over the inner end of either 30 of the pawls and act against the tension of the spring so as to hold one of the pawls out of engagement with the teeth 12 and when in such position allow the other pawl to be moved through the recess by the spring and thus be held in engagement with the teeth. The shoulders 20 are preferably arranged at diametrical points and it will be appreciated that by rotating the band 18 in the reverse direction, the pawl that is in engagement 40 will be removed from engagement with the teeth, while the pawl that was held out of engagement will be allowed to engage the teeth, and of course by swinging the handle from side to side, the shank will be adjusted 45 step by step to consequently move the jaw 6. A pin 22 is mounted in the ends of the sections 13 against the outer edge of the band to prevent accidental disengagement thereof while a retaining ring 23 is mounted on the outer ends of the sections 13 to hold the sections in close relation with respect to each other at this point, the ring being held in position by means of fastening devices 26. Another fastening device 27 is extended 55 transversely through the semi-circular sections adjacent the disks to hold them in substantially rigid relation with respect to each other at such point. If desired, it is to be understood that the handle sections may 60 be formed in one piece. This would obviate the employment of the retaining means or the fastening devices.

The preferred means for rigidly connecting the block 8 to the arm 5 consists in providing the outer face of the arm with a re-

cess 28, the transverse wall of which serves as a shoulder and in which recess is seated, a plate 29 desirably of a rectangular configuration. The adjacent face of the block is also provided with a recess 30 which forms 70 a shoulder 31 and seated within this recess is another plate 32 which is secured to the block by suitable fastening devices 33 while the outer end thereof is bent and secured to the outer face of the arm by means of suitable fastening devices 34. Fastening devices 35 also extend from the inner wall of the recess 10 in the block through the arm. By the arrangement of this connecting means, the strain imposed on the block and 75 the bracket arm is equalized throughout the entire adjacent surfaces of these parts. If desired, the block may be cast with the arm. For the purpose of adjustably connecting the sections for removably holding them in 80 relatively adjusted positions, the section 2 is provided with a plurality of transversely extending openings 36 arranged at suitable distances with respect to each other and adapted for registration with certain of the 85 opposed transverse openings 37 in the sides of the channel-shaped section 1. The intermediate portion of the channel-shaped section is also provided with a plurality of rectangular openings 38 and engageable in any 90 one of the openings 38 is a lug 39 formed upon the body of the adjacent section 2 which is slidably received between the sides of section 1. The sides of the channel-shaped section 1 are provided on their outer 95 surface adjacent their free edges with opposed longitudinal grooves 40 while disposed about the channel-shaped section is a channel-shaped slide 41. Opposed longitudinal ribs 42 are formed on the inner surface 100 of the slide 41 and are slidably engageable with the grooves 40 which serve to guide the sliding movement of the slide. The sides of the slide are now provided with opposed 105 openings 43 adapted for registration with certain of the aligned openings 36 and 37 in the sections 2 and 1. The intermediate portion of the slide is provided with a transverse slot 44 which is in alignment with the openings 43 while the edges of the slot adjacent the bottom thereof are provided with opposed grooves 45. Slidably mounted in the grooves and slot and in the openings 43 is improved retaining means for holding the sections in a relatively adjustable position 110 and is indicated in its entirety by the numeral 46, and in the present instance consists of a body 47 from the inner face of which extends a keeper pin 48 which is removably engageable with the aligned openings 36 and 37 and 43 in the sections and in the slide. A guide arm 49 extends from the lower end of the body at approximately 115 right angles thereto and is engageable with the slot 44. Flanges 50 extend from the op- 120

125

130

135

posite edges of the arm and coöperate with the grooves 45 for guiding the sliding movement of the arm. A retaining clip 51 is extended across the slot and is connected at 5 its ends to the intermediate portion of the slide, and coöperating therewith is a stop 52 rigidly connected to the outer end of the arm for preventing accidental displacement of the means which removably holds the sections 10 in their relatively adjusted position.

Coöperating with the means for holding the sections in a relatively adjusted position is the improved maintaining means which serve to prevent accidental disengagement 15 of the retaining means when they are fully extended. In reducing this feature of the invention to practice, a U-shaped plate 53 is secured to the inner end of the channel-shaped section 1. Side arms of the plate extend beyond the free edges of the sides of 20 the channel-shaped section and terminate in opposed eyes 54 in which is removably mounted a bolt 55 held in an operative position by means of a nut 56.

25 The mode of operation of the present invention may be reviewed as follows:

In adjustably connecting the sections in a pre-determined position a section 2 is slid in the section 1 a certain distance whereupon 30 the lug 39 is engaged in one of the openings 38 so as to aline certain of the openings 36 and 37. The slide is now adjusted so that the openings 43 thereof aline with the registered openings 36 and 37 whereupon the 35 keeper pin 48 is engaged therein, the arm 49 serving to guide the pin during movement. The sections being now arranged in their properly adjusted position are arranged adjacent a piece of work, not shown, 40 so that the stationary jaw 4 engages one side of the work. To guide the movable jaw the governor band is adjusted to withhold one of the pawls from engagement with the teeth 12 and to allow the opposite pawl to be 45 yieldingly held in engagement with one of the teeth by means of the spring 17. The handle is swung back and forth so that the adjacent sleeve nut will move the movable jaw upwardly until it comes into engagement with the opposite side of a piece of 50 work.

It is thought in view of the foregoing description that a further detail description of the mode of operation of the invention is 55 entirely unnecessary. Likewise, it is thought that the advantage of the invention will be readily understood. At this point, however, it may be mentioned that, if desired, cushions may be placed on the outer face of 60 the jaws to prevent marring of the work, especially when a piece of furniture is to be clamped.

As many changes could be made in the above construction and many apparently 65 widely different embodiments of this inven-

tion could be made without departing from the scope thereof, it is intended that all matter contained in the above description or shown in the accompanying drawings shall be interpreted as illustrative and not in a 70 limited sense. It is also to be understood that the language used in the following claims is intended to cover all the generic and specific features of the invention herein described and all statements of the scope of 75 the invention, which, as a matter of language might be said to fall therebetween.

Having thus described this invention, what is claimed as new and desired to be secured by Letters-Patent, is:

1. A device of the character described including a pair of sections one of which is slidably receivable within the other, each of the sections being provided with a plurality of openings adapted for alinement 85 with each other, a slide adjustably mounted on the outer section, retaining means operably mounted on the slide and engageable with certain alined openings in the sections for removably holding the sections in relatively adjusted position, a stationary jaw 90 formed on one end of one section, and a movable jaw adjustably mounted on the other section for coöperating with the stationary jaw.

2. A device of the character described including a pair of relatively adjustable sections one of which is channel-shaped in cross section while the other is rectangular in cross section and is slidably received 100 within the channel-shaped section, both of the sections being provided with transverse openings for alinement with each other at times, the channel-shaped section being provided on its outer surface with opposed 105 grooves, a channel-shaped slide disposed about the channel-shaped section, ribs on the inner surface of the slide slidably engaging the grooves, the sides of the channel-shaped slide being provided with opposed openings 110 for registration with certain alined openings in the sections, a keeper pin slidably mounted on the slide for removably engaging the slide and the sections, means for preventing accidental disengagement of the keeper pin 115 from the slide, a rigid jaw formed on one of the sections and an adjustable jaw mounted on the other section for coöperating with the rigid jaw.

3. A device of the character described including a pair of sections one of which is channel-shaped in cross section while the other is rectangular in cross section for slide- 120 able engagement with the channel-shaped section, the channel-shaped section being provided near its sides with opposed open- 125 ings and in its intermediate portion with other openings, the rectangular-shaped section being provided with openings for registration with certain of the opposed open- 130

ings, a lug on the rectangular-shaped section for engaging one of the openings in the intermediate portion to hold certain of the openings in the sides of the channel-shaped section in alinement with certain of the openings in the rectangular-shaped section, the outer surface of the sides of the channel-shaped section being provided with opposed longitudinal grooves, a channel-shaped slide disposed about the channel-shaped section, ribs on the inner surface of the sides of the slide for engagement with the grooves, and a keeper pin adjustably mounted on the slide for engagement with the alined openings in the sections for removably holding the sections in adjusted position.

4. A device of the character described including a pair of sections one of which is channel-shaped in cross section while the other is rectangular in cross section for sliding engagement with the channel-shaped section, both of the sections being provided with openings for alinement with each other, a channel-shaped slide slidably mounted on the channel-shaped section, the intermediate portion of the slide being slotted while the sides thereof are provided with opposed openings, a retaining member including a body, a keeper pin projecting from the body for engagement with the alined openings in the sections, an arm engageable in the slot for guiding the sliding movement of the keeper, a clip carried by the slide, a stop carried by the arm for cooperating with the clip for preventing accidental displacement of the retaining member, means on the channel-shaped section for coöperating with the keeper in preventing accidental disengagement of the sec-

tions, a rigid jaw formed on one of the sections and an adjustable jaw mounted on the other section for coöperating with the rigid jaw.

5. A device of the character described including a pair of relatively adjustable sections, means for removably holding the sections in various positions of adjustment, a bracket arm extending from one of the sections, a rigid jaw formed on the bracket arm, another bracket arm extending from the other section and longer than the first-mentioned bracket arm, a block carried by the long bracket arm and provided with a recess and further provided with a threaded longitudinal bore, a threaded shank adjustably mounted in the bore, another jaw swiveled on the outer end of the shank and disposed opposite to the rigid jaw, an adjusting sleeve nut mounted on the shank and positioned within the recess, a plurality of teeth formed on the periphery of the nut, a handle, spaced disks formed on the inner end of the handle and provided with openings for partial rotary movement about the nut upon the opposite sides of the teeth, opposed pawls pivotally mounted between the disks, an expansion spring between the outer ends of the pawls for normally holding the inner ends thereof in yielding engagement with the disks, and a governor band partially rotatable mounted on the handle for alternately holding either one of the pawls out of engagement with the teeth so that when the handle is swung the free pawl will adjust the shank to consequently adjust the jaw.

In testimony whereof I affix my signature.

ANTHONY J. HEROLD.
